HENRY E. WILSON, OF PEMBERTON, MINNESOTA.

SNOWPLOW AND DISTRIBUTING ATTACHMENT FOR ROAD-SCRAPING MACHINES.

Application filed March 25, 1925. Serial No. 18,145.

This invention relates to snow plow attachments for road scraping or grading machines, whereby the standard road scraper may be converted into a highly efficient snow plow and snow distributor.

The greatest objection to snow plows used on rural roads is that the snow is banked up on the sides of the roads, forming walls of considerable height before the winter is over. Falling snow, drifts between these walls, often collecting to a considerable depth. When the road is again plowed, much difficulty is, of course, encountered, going through these drifts and again turning off the snow to the sides of the road. Moreover, the walls at each side of the road increase in width each time the road is plowed, consequently narrowing the driving space of the road.

It is the main object of this invention to provide an attachment for a road scraping machine which will permit the snow to be plowed by the usual road scraping blade and distributed over the shoulder of the road or in the ditch at one side of the road where it will not bank and form the objectionable walls at the sides of the road. The attachment is also well adapted for distributing sand, dirt and gravel on the shoulder of the road.

It is a further object of the invention to provide an auxiliary blade adapted to overhang the shoulder of a road and to receive the snow from a diagonally disposed road scraping blade and distribute the same over the shoulder of the road and in the ditch adjacent thereto. The snow is thus not only removed from the road but spread out where it will more quickly be melted and evaporated.

It is a further object of the invention to provide an outwardly extending auxiliary blade secured to one end of the road scraping blade having its bottom edge disposed some distance above the bottom edge of the road scraping blade.

A still further object of the invention is to provide means rigidly secured to one of the back wheels of the machine, or the side of the frame, to prevent lateral skidding of the machine due to the side pressure exerted by the auxiliary blade in plowing and distributing the snow. The co-operation of this non-skidding means is found necessary to efficiently plow and distribute the snow as desired.

It is a more specific object of the invention to provide in such a device a pivoted auxiliary blade adapted to extend over the shoulder of the road having means for limiting its downward position, having draft means connected to its outer end, and provided with means for raising or lowering said blade to a desired position.

A still further object of the invention is to provide a snow plow and distributing attachment for standard road scraping machines capable of being secured to function at either side of the scraper blade.

These and other objects of the invention will be apparent from the following description made in connection with the accompanying drawings, wherein like notations refer to similar parts throughout the several views, and in which

Fig. 1 is a cross section through the front portion of a standard road scraping machine having the preferred form of the invention mounted thereon, showing most of the parts in elevation;

Fig. 2 is a plan view of the device mounted on a road scraping machine with some parts of the machine being broken away;

Fig. 3 is a rear elevation of the auxiliary blade attached to the blade of the scraping machine;

Fig. 4 is an enlarged fragmentary rear elevation of the attaching means for said blades with some parts detached;

Fig. 5 is a vertical section taken on the line 5—5 of Fig. 4;

Fig. 6 is a side elevation of the non-skidding runner rigidly secured to one of the back wheels of the scraping machine;

Fig. 7 is a vertical section taken on the line 7—7 of Fig. 6, and

Figure 8 is a detailed view showing the means for quickly elevating the auxiliary blade to prevent interference thereof with obstacles on the road.

In Figs. 1 and 2 a standard road scraping machine is illustrated having the main frame 8 mounted on the front and rear wheels 9 and 10 respectively, the sub-frame 11 extending from the front of the machine to approximately the central portion thereof below frame 8 and carrying the ring or circle 12 on which the semi-annular member 13 is slidably mounted, constituting a turn-table for supporting a scraper blade 14. The blade 14 is secured to the turn-table 13 by means of the depending arms 15, and is

usually of sufficient length to traverse the distance between the outer sides of the back wheels, preferably having a concave front side. The usual sharpened cutting edge 14^a is secured to the bottom edge of the blade 14. Operating wheels 16 engaging suitable mechanism for raising or lowering the two ends of the blade 14 and thereby varying the angle of said blade, are mounted on the 10 rear portion of the main frame 8. The turn-table is supported from the sub-frame 11. The rear axle housing 17 is secured to the rear ends of the main frame 8 and the front truck is pivoted to the main frame by the 15 king bolt 18.

The invention in its preferred form comprises several co-operating devices adapted to be readily attached to the standard road scraping machine. An elongated auxiliary 20 blade 19 of approximately the same length and thickness as the scraping blade 14 is provided having the centrally projected apertured tongues 19^a at either end thereof, the lower portions of the ends of the blade 25 proper extending at right angles to the bottom of the blade and affording the square shoulders 19^b, the purpose of which will later be explained. The end portions of the blade 19, above the tongues 19^a, are cut on an oblique line affording the oblique shoulders 19^c, extending inwardly somewhat with respect to the square shoulders 19^b. A cutting edge 20 is secured to the bottom edge of the blade 19 at the front side thereof, having its ends 30 spaced slightly from the shoulders 19^b of said blade. The scraping blade 14 is provided at its end portions with three vertically spaced apertures therethrough, and channeled plates 22 having the lower square shoulders 22^a and the upper oblique shoulders 22^b, are provided, also carrying the 35 central bosses 23 and having the three vertically spaced apertures therethrough in alinement with the apertures in the ends of scraping blade 14. The apertures in the tongues 19^a of the auxiliary blade 19 are of slightly greater size than the boss 23 so that the blades may be pivoted together about the boss 23 and secured within the channel plate 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

thereby co-operating to limit the downward position of the auxiliary blade. The upper shoulder 19^c of the blade 19 being set slightly back permits the auxiliary blade to be 70 swung upwardly until the top edge of the tongue 19^a contacts against the angular shoulder 22^b of the channel plate 22. It is 75 obvious that the auxiliary blade 19 may be similarly mounted at either end of the scraping blade 14, always being attached to the rear end of blade 14 when the same is diagonally disposed with reference to the longitudinal center of the frame. The attachment is only operative when the scraping blade is disposed in a transverse diagonal 80 position.

The outer plates 24 have slots adjacent their ends and a central aperture so that the blades when pivotally connected may be 85 readily detached by taking out the central bolt and simply loosening the upper and lower bolts.

A flexible member 25 is secured at one end to the top intermediate portion of the blade 19 and passes over the sheave 26, having its other end made fast to the operating lever 27 located adjacent the driver's platform on the machine. The lever 27 thus controls the position of blade 19 and may be quickly manipulated to raise the free end of said 95 blade as desired.

A transverse arm comprising two angularly extending members 28 and 29, is secured across the sub-frame 11 of the machine 100 forwardly of the blades. The lower member 28 is bent upwardly at a point beyond the outer side of frame 11, while the upper member 29 is bent upwardly from a line across the inner side of the same portion of frame 11, said members 28 and 29 being clamped 105 together between the sides of frame 11 and also at a point adjacent their outer extremities. A wedge block 29^a is driven between the angle formed by members 28 and 29 at a point directly over one side of the frame 11 110 traversing the arm and being secured to frame 11 by means of bolts at either side of said arm. A depending loop or hook 30 is secured to the outer end of the members 28 and 29, through which a flexible member 31 is passed having one of its ends secured to the free end of the blade 19 through the aperture in the tongue 19^a and having its other end preferably secured to the king bolt 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

In order to furnish an efficient base of resistance for the work done by the auxiliary blade projecting from one side of the machine, a non-skidding runner is provided 125 rigidly secured to one of the rear wheels 10, preferably the rear wheel on the opposite side of the machine from the auxiliary blade 19. This runner comprises a relatively thick horizontal body portion 32 having an outwardly curved sharpened cutting edge 33 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

secured to the bottom edge thereof and adapted to cut into the snow, ice or ground and prevent the back portion of the machine from skidding laterally, due to the resistance of the snow against the auxiliary blade.

Obviously, the auxiliary blade disposed wholly on one side of the machine and adapted to overhang the shoulder of the road, must have a firm base of resistance.

Such a runner has been found to be the only means whereby the back portion of the machine will be prevented from any skidding. The runner is preferably secured to the wheel 10 by means of a plurality of hooks

34 having their outer ends threaded and bolted against the outer side of the body portion 32. The runner is further secured and braced by means of the diagonal brace bar 35, best shown in Fig. 7, the inner end 20 of which is secured to the rear axle housing 17. The guard chain 36 connects the front end of the runner with the main frame 8.

It is obvious that, as has been stated, the auxiliary blade as well as the runner and arm for receiving the draft means, may be disposed on the opposite sides of the machine, thereby reversing the entire attachment. This is desirable oftentimes when one side of the blade 14 or blade 19 becomes

worn. In order to reverse the attachment, the scraping blade 14 must, of course, first be swung on the turn-table to the opposite diagonal position with reference to the longitudinal center line of the machine.

The operation of the device is probably obvious but may be briefly summarized as follows:

The auxiliary blade is preferably lowered to a substantial horizontal position and the machine pulled along the side of the road with the auxiliary blade overhanging the shoulder of the road and the ditch at the side thereof. The scraping blade 14 will cut the ice and snow and plow the same, pushing the plowed snow outwardly and backwardly to the auxiliary blade. The auxiliary blade will spread the snow out and distribute the same over the shoulder and ditch of the road, thereby entirely removing the snow from the travelled portion of the road and preventing a ridge of snow from accumulating at the sides.

The auxiliary blade 19 is so pivoted to the scraping blade 14 that the bottom edge of blade 19, when in horizontal position, will extend at a considerably higher level than the cutting edge of blade 14, preferably four or five inches thereabove. The purpose of this construction is to enable the auxiliary blade to pass freely over any ice or crust adjacent the outer end of the scraping blade, thereby not disturbing the crust or cutting into the snow but merely pushing the plowed snow backwardly and outwardly and distributing the same into the ditch

at the side of the road and over the shoulders of the road. The raised level of the auxiliary blade therefore lessens the resistance of the snow thereon and permits the snow to be distributed and spread out evenly due to the receiving shoulder of the road.

The draft device for the outer end of the auxiliary blade properly holds said blade in operative position, while the lever 27 permits the blade 19 to be quickly raised as desired.

From the above description, it will be seen that an extremely simple but highly efficient attachment has been invented for a standard road scraping machine capable of being readily attached or detached. Extensive actual usage of the device has shown the same to be highly successful for the purposes intended including the distribution of gravel, sand and dirt.

It will, of course, be understood that various changes may be made in the form, details, proportions and arrangement of parts without departing from the scope of the invention, and that the device may be equally well applied to other types of grading or road-working machines than the type illustrated in the accompanying drawings.

What is claimed is:

1. In a road scraping machine having a frame and a blade carried thereby at an oblique angle to the longitudinal center line thereof, an attachment of the class described comprising an auxiliary blade pivoted at its inner end to the rear end of said scraping machine blade, and adapted to overhang the shoulder of a road and distribute the plowed material thereover, means carried by said auxiliary blade for limiting the downward position thereof and normally hold the same substantially in alignment with said scraping machine blade, and means for suddenly swinging said auxiliary blade upwardly to clear an obstacle at the side of the road.

2. The structure set forth in claim 1, and said means comprising a lever on said frame and a flexible member connecting said lever with the intermediate portion of said auxiliary blade.

3. A distributing and plowing attachment for a road scraping machine, said machine being provided with a wheeled frame and a scraping blade carried at an oblique angle thereto comprising an auxiliary blade secured at one end to the rearward end of said scraping blade, adapted to overhang the shoulder of a road and distribute the plowed material thereover, and a runner secured to one of the rear wheels of said frame adapted to furnish a base of resistance to permit said auxiliary blade to distribute material when said scraping machine is moving forwardly.

4. In a road scraping machine having a

- wheeled frame and a blade carried thereby at an oblique angle to the longitudinal center line of said frame, a distributing and plowing attachment of the class described 5 comprising an auxiliary blade secured at its inner end to the rear end of said machine blade, projecting outwardly therefrom in substantial alinement with and adapted to overhang the shoulder of a road and dis- 10 tribute the plowed material thereover, and an outwardly extended and sharp edged runner rigidly secured to the bottom of one of the back wheels of said frame adapted to furnish a base of resistance to the dis- 15 tributing action of said blade.
5. In a road scraping machine having a frame and a blade carried thereby at an oblique angle to the longitudinal center line thereof, an attachment of the class described

comprising an auxiliary blade pivoted at 20 its inner end to the rear end of said scraping machine blade, and adapted to overhang the shoulder of a road and distribute the plowed material thereover, a recessed plate 25 secured adjacent one end of said scraping blade provided with a stop shoulder and one end of said auxiliary blade provided with a tongue pivoted in the recessed portion of said plate and provided with a co- 30 operating stop shoulder adapted to co- operate with said first mentioned stop shoul- 35 der to normally hold said auxiliary blade in alignment with said scraping blade oper- ative to distribute plowed material.

In testimony whereof I affix my signa- 35

HENRY E. WILSON.
